US0D1035500S

(12) **United States Design Patent** (10) Patent No.: **US D1,035,500 S**
(45) Date of Patent: ** Jul. 16, 2024

(54) **MOPED**

(71) Applicant: **Changsha Xiaoxiao Intelligent Technology Co., LTD**, Changsha (CN)

(72) Inventor: **Binjie Yang**, Hunan (CN)

(**) Term: **15 Years**

(21) Appl. No.: **35/517,306**

(22) Filed: **Mar. 3, 2023**

(80) **Hague Agreement Data**

Int. Filing Date: **Mar. 3, 2023**

Int. Reg. No.: **DM/228946**

Int. Reg. Date: **Mar. 3, 2023**

Int. Reg. Pub. Date: **May 26, 2023**

(30) **Foreign Application Priority Data**

Sep. 6, 2022 (CN) 202230587918.6

(51) **LOC (14) Cl.** **12-11**

Primary Examiner — Darlington Ly

(57) **CLAIM**

The ornamental design for a moped, as shown and described.

DESCRIPTION

The file of this patent contains at least one drawing/photograph executed in color. Copies of this patent with color drawing(s)/photograph(s) will be provided by the Office upon request and payment of the necessary fee.

1. Moped

1.1 is a top, front and left-side perspective view of a moped embodying my new design;

1.2 is a left-side view thereof;

1.3 is a right-side view thereof;

1.4 is a front view thereof;

1.5 is a rear view thereof;

1.6 is a top view thereof; and

1.7 is a bottom view thereof.

1 Claim, 7 Drawing Sheets
